UNITED STATES PATENT OFFICE.

ROY L. DAVID, OF SAN JOSE, CALIFORNIA.

HEADING-KNIFE FOR MILO AND THE LIKE.

1,286,548.

Specification of Letters Patent.

Patented Dec. 3, 1918.

Application filed January 11, 1918. Serial No. 211,388.

To all whom it may concern:

Be it known that I, ROY L. DAVID, a citizen of the United States, and a resident of San Jose, in the county of Santa Clara and 5 State of California, have invented a new and Improved Heading-Knife for Milo and the like, of which the following is a full, clear, and exact description.

My invention relates to heading knives 10 adapted to be applied to the right or left hand, or both, and is more particularly intended for use in harvesting milo, Kafir corn, Egyptian corn, and the like.

Particularly the invention relates to heading knives of the type including a finger blade and a coacting relatively fixed cutter disposed on the hand at the palm.

Objects of the invention are to improve heading knives of the character indicated 20 with respect to the form and relation of the finger blade and coacting cutter; to provide a novel hand-piece mounting the relatively fixed cutter; to provide a novel arrangement of straps for securing the hand-piece to the 25 hand; to provide a novel finger-piece on the finger blade; to provide a finger strap novel in its relation to the finger-piece.

Other objects of the invention and various distinctive features will appear as the description proceeds.

Reference is to be had to the accompanying drawings forming a part of this specification in which similar reference characters indicate corresponding parts in all the 35 views, it being understood that the drawings are merely illustrative of one example of the invention.

Figure 1 is a perspective view showing one of my devices as applied to the left 40 hand, the view showing the hand closed, following the cutting and grasping of the head of milo or corn after the same has been severed from the stalk, a portion of the stalk from which the head has been severed 45 being indicated;

Fig. 2 is a front perspective view showing one of my devices applied to the right hand, the hand being open;

Fig. 3 is a front view of the device shown 50 applied in Fig. 2, illustrating the pivoted finger blade in the closed position, portions of the hand straps being broken away;

Fig. 4 is a side elevation of the right hand heading knife shown in Figs. 2 and 3, illus-

trating the same with the finger blade swung 55 to the open position, and showing the buckled position of the hand straps.

Fig. 5 is a front view with the parts in the position shown in Fig. 4;

Fig. 6 is a fragmentary view showing the 60 finger-piece with the cutter removed and portions of the hand straps being broken away;

Fig. 7 is a cross section on the line 7—7, 65 Fig. 4.

In forming a heading knife in accordance with my invention a pressed metal hand-piece 10 is produced having along the rear edge thereof a flange 11 curved to conform generally to the hand at the rear portion 70 of the palm. At the front the hand-piece has a notch or cutaway as at 12. At the thumb side of the finger piece 10 a curved arm 13 is produced to lie between the thumb and the first finger and to extend to the 75 back of the hand. In practice, the curved arm 13 is covered with leather or like soft material 14. The position of the curved arm with its covering will be clear from a comparison of Figs. 1 and 2. The covering 80 14 is shown held in place by rivets 15 and one of said rivets serves to secure one end of a hand strap 16 which extends partially across the back of the hand as best seen in Fig. 1, the free end of the strap 16 being 85 passed through a tongue buckle 17. The buckle 17 is on one end of a wrist strap 18 which is secured as by a rivet 19 or other means intermediate the ends of said strap 18 to the finger-piece 10 at the side opposite 90 the thumb arm 13. Said buckle 17 in addition to adjustably receiving the free end of the back strap 16 receives also the free end of the wrist strap 18.

A cutter 20 is rigidly secured to the hand-piece 10. In the preferred arrangement the material of the hand-piece, at one side of the notch 12, is pressed upward to form a bracket 21 to which the knife 20 is secured. Said bracket 21, as best seen in Figs. 4, 5 95 and 6, receives bolts 22, 23 for bolting the cutter 20 in place. One bolt 22 extends through a bolt hole 24 in the bracket 21 while the other bolt 23 extends through a slot 25 which is of such shape and size as 100 to permit a limited adjustment of the cutter 20 through an angle with the bolt 22 and bolt hole 24 as a center as seen best in

Fig. 4. Besides the bolt holes formed in the cutter 20 to receive the bolts 22, 23, an additional bolt hole 22^a is formed as seen in Fig. 4, so that the blade may be moved forwardly on the hand-piece 10 by placing the bolt 22 in said bolt hole 22^a instead of the position occupied by said bolt in Fig. 4, the bolt 23 then extending similarly through the slot 25 but through the cutter 20 in the position at the bolt hole through which the bolt 22 extends in Fig. 4. The adjustment of the cutter 20 is to accommodate the said cutter and the position of the finger blade to the hand of the user.

15 The finger blade 26 is pivoted to the cutter 20 by a rivet 27 or the like, so that said finger blade and cutter constitute in effect an articulated knife. Thus, the finger blade may be moved to or from the cutting relation of the cutter 20 by a closing of the hand. The outward movement of the blade 26 is limited by coacting stop elements on said blade and on the cutter 20, said cutter having a stop lug 28 at its forward end 20 against which a lateral stud or pin 29 on the blade 26 may contact.

Secured to the finger blade 26 is a finger-piece 30 presenting arms at each side of said blade to receive the second and third fingers. 30 The finger-piece is arched at the center as at 31, the sides of the arch being spaced to snugly accommodate the blade 26 as clearly shown in Fig. 3. An effective manner of securing the blade 26 in the arch 31 is to 35 form a transverse hole 32 in Fig. 7 in said blade and punch the material of the one side of the arch as at 33 into said hole and against the opposite side of the arch. A finger strap 34 is provided on the finger-piece 30 and extends freely at the approximate center of the strap through a loop or keeper 35 on the arch of said finger-piece. The opposite ends of the strap 34 are turned under the respective arms of the finger-piece 40 and adjustably secured thereto, there being shown for the purpose, holes 37 in the ends of the strap and a spur 38 on each arm of the finger-piece 30. Thus, either hole 37 on an end of the strap 34 may be 45 brought into position to receive the adjacent spur 38 for varying the effective size of the strap 34. The arrangement is such that said strap at the sides of the arch 31 and loop 35 receives the second and third fingers of a 50 hand, the strap being free to accommodate itself to the size and movements of the respective fingers.

With the described construction of hand-piece 10 and described arrangement of the straps 16, 18, said hand-piece is firmly secured in position and may be adjusted with facility and despatch; at the same time the minimum discomfort is afforded the user. The manner of using the device will be obvious from the foregoing and it will be clear

that both hands may be employed to grasp the stalk *a* in a manner to permit the head *A* to be severed and be held simply by the closing of the hand. It will be seen from a comparison of Figs. 1 and 2 that the cutter has such a form and dimensions that the front end thereof will extend between the second and third fingers at the base thereof, and said fingers will be positioned on the finger 30 at the sides of the blade 26. The arms of the finger-piece are curved transversely. Also the securing of the hand-piece and the finger blade with its finger-piece is independently effected, the sole connection between the finger blade and its appurtenances and the cutter being through the medium of the pivot 27. The arrangement permits of the fingers accommodating themselves to the cutting and grasping movements with the maximum freedom and minimum strain.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim as new, and desire to secure by Letters Patent:

1. A heading device of the class described including a hand-piece, means to secure the same to a hand, a cutter on the hand-piece, a finger blade pivotally mounted at the front end of the cutter, a finger-piece on said blade, the finger-piece being arched at the approximate center and presenting lateral arms at each side of the blade, the arched portion of the finger piece having spaced sides between which the blade is secured, and a finger strap on said finger-piece, the ends of the strap being secured to the arms of the finger-piece.

2. In a device of the class described having a cutter, and means to secure the cutter on the hand; a finger blade pivotally connected with the cutter, means on said blade presenting lateral arms at the sides of the blade to receive the fingers, a finger strap secured at its ends at each side of the blade and extending over the latter, and a loop at the back of the finger blade through which loop said strap freely passes.

3. In a device of the class described having a cutter, and means to secure the cutter on the hand; a finger blade pivotally connected with the cutter, means on said blade presenting lateral arms at the sides of the blade to receive the fingers, a finger strap at the back of the blade, said strap having at the ends thereof series of holes and spurs on the arms of the finger-piece optionally receivable in the holes of the strap to adjustably retain the strap in position.

4. In a device of the class described having a cutter, and means to secure the cutter on the hand; a finger blade pivotally connected with the cutter, a finger piece on the blade and presenting lateral arms at each side of the blade and an approximately central arch, the arch having spaced sides between which the blade is received, said blade having a transverse hole and one wall of the arch of the finger-piece having an ¹⁰ indentation extending into said hole in the blade.

ROY L. DAVID.
